(57) **CLAIM**

The ornamental design for a battery, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a battery according to our new design;

FIG. 2 is another perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top elevation view thereof; and

FIG. 8 is a bottom plan view thereof.

FIG. 9 is a perspective view of a battery according to another embodiment of our new design;

FIG. 10 is another perspective view thereof;

FIG. 11 is a front elevation view thereof;

FIG. 12 is a back elevation view thereof;

FIG. 13 is a right side elevation view thereof;

FIG. 14 is a left side elevation view thereof;

FIG. 15 is a top elevation view thereof; and,

FIG. 16 is a bottom plan view thereof.

The broken lines represent an example environment of the claimed design, and are for illustrative purposes only. The broken lines form no part of any embodiment of the claimed design.
